UNITED STATES PATENT OFFICE.

RUDOLPH M. HUNTER, OF PHILADELPHIA, PENNSYLVANIA, ASSIGNOR, BY MESNE ASSIGNMENTS, TO EVERLASTING VALVE CO., A CORPORATION OF NEW JERSEY.

VALVE.

14,687.

Specification of Reissued Letters Patent. Reissued July 15, 1919.

Original No. 1,189,950, dated July 4, 1916, Serial No. 866,921, filed October 16, 1914. Application for reissue filed June 4, 1918. Serial No. 238,220.

To all whom it may concern:

Be it known that I, RUDOLPH M. HUNTER, a citizen of the United States, and resident of Philadelphia, county of Philadelphia, 5 and State of Pennsylvania, have invented an Improvement in Valves, of which the following is a specification.

The object of my invention is to provide a construction of through-valve especially 10 designed as a blow-off valve, or where quick action is required.

In general construction, my invention essentially consists of a body having a valve chamber provided with inlet and outlet 15 ports in alinement, associated with controlling means for the outlet port comprising a rocking spindle extending through the body on the side having the outlet port and provided with an annular collar portion on 20 its inner end seating upon a packing ring on the inner face of the body, the said spindle being yieldingly drawn axially outward by a coil spring arranged outside of the valve chamber, to insure sealing of its collar, and said rocking spindle operating a 25 lateral arm reaching over the outlet port and operating a spring pressed valve piece movable over the outlet port.

My invention also comprehends other features of construction which, with those above stated, are fully described hereinafter and more particularly defined in the claims.

Referring to the drawings:—Figure 1 is a sectional elevation of my improved valve, 35 taken on line $x-x$ of Fig. 2; Fig. 2 is an inverted plan view of the upper portion of the valve looking in the direction of the dotted line $y-y$, and with the spindle in section; and Fig. 3 is a sectional view of a 40 modified form of the inlet nozzle.

The valve body is formed of the two parts 2 and 3 which have an annular engaging face with an interposed ductile metal packing ring 4 and clamped together by bolts 5. 45 The part 2 of the body is in general contour flat on its upper surface, but has the valve seat 13 slightly higher than the annular surface 4^a containing the packing ring 4, this higher level of the seat being to enable 50 it to be surfaced in case of wear, either by planing or by turning, as may be desired. The valve seat 13 for the valve piece 26 has an outlet port 12. The port 12 has an outlet 7 which may be screw-threaded or other-

wise formed for suitable connection with 55 piping. This outlet valve seat 13 is controlled by an outlet valve piece 26, spring pressed upon its seat. The other part 3 of the valve casing is made with a recessed interior or valve chamber to provide space for 60 the valve mechanism, and provided with a port 8 preferably surrounded with a valve seat 11 which has a laterally extended portion 11^a as a guide for the valve piece 27. The valve seat 13 of the body part 2 is constructed with a lateral extension corresponding to 11^a of the valve seat 11, so that the opposing valve seats may be uniform and provide surfaces between which the valve pieces 26 and 27 travel. The port 8, constituting the inlet port, has outwardly flaring 70 walls 10 providing an expansion chamber 9 which terminates at its outer part in an inlet 6 which may be screw-threaded or otherwise formed for receiving the steam or other 75 fluid to be controlled. The ports 8 and 12 are of the same diameter, but the flaring walls 10 of the port 8 act to cause the steam or fluid to converge when passing from the port 8 to the port 12 when the valve is open, 80 and thereby avoid causing scale or solid matter from cutting away the valve seat 13. To form the conical or inclined walls 10, the chamber 9 is provided, which is an enlargement over the diameter of the supply 85 pipe which would be screwed into the inlet 6. In other words, the inlet pipe and the outlet pipe, as well as the ports 8 and 12, may be all of the same diameter, but by allowing the fluid to converge in passing 90 through the port 8, it will be delivered into the discharge pipe through the port 12 without being caused to directly impinge upon the edges of the port 12 or the valve seat surface 13. This is especially important in 95 high pressure work. It is of course manifest that the inlet pipe may be larger in diameter than the area of the port 8, and this is indicated by the construction shown in Fig. 3. It is preferable, however, that 100 the sizes of the pipes connecting with the inlet and the outlet portions of the valve should be the same, but this may be varied to suit the wishes of the designer.

22 is a swinging arm, which is rocked by 105 and movable with a spindle 14 journaled in the part 2 of the casing. This arm 22 is bored out to receive the cylindrical hub por-

tions 28 and 29 of the respective valve pieces 26 and 27, so that they are carried with the swinging arm, but at the same time have capacity for adjustment transversely thereto 5 and relative to their respective seats. These hub portions 28 and 29 of the valve pieces are recessed to provide a compartment in which is located a spring 30, the same acting to force the two valve pieces 26 and 27 10 against their respective seats.

The pivotal part of the arm 23 is secured to the rocking spindle and preferably provided with a socket, shaped to receive the head 16 of the spindle, which is so formed 15 as to cause the arm to be positively oscillated by any rotation of the spindle itself just as though it was integral with the spindle. This spindle is provided with a collar 15 immediately to one side of the head 16 and 20 arm 22. The spindle 14 fits through a bearing aperture 19 in the part 2 of the casing, and is surrounded by a packing ring 21, which is preferably of copper and arranged in an 25 annular recess 20 in the casing and immediately under the collar 15 of the spindle, the said collar preferably extending somewhat into the recess, as is clearly shown. In 30 this manner, the collar makes a rotary packed joint upon the packing, and the normal tightness of the joint is increased by the pressure in the valve chamber on the inside of the valve casing, said pressure forcing the collar upon the packing. The hub part 35 of the arm 22 is preferably snugly fitted 35 between the collar 15 and the inner face of the wall of the part 3 of the casing, so that there is freedom of rotation but practically no end play, and this construction at the same time permits the movement of the 40 spindle longitudinally to insure the collar 15 pressing upon the packing ring 21. The opposite end of the swinging arm 22 is preferably provided with a lug 24 which fits in a curved guideway or groove 25 through 45 which it freely travels when the spindle is rocked. By means of this guide way and the lug 24 projecting from the arm 22, it will be seen that the said arm is supported at both ends and as the valve pieces are 50 spring pressed upon their seats the said arm does not interfere with the free adjustment of the valve pieces 26 and 27 in relation to their seats. It merely acts as a means of holding the said valve pieces in alignment 55 and closing the gap between them, and so that the spring 30 is shielded within a chamber which does not become clogged with dirt. Moreover, in this construction, the spring is 60 fully shielded from direct action of the steam or hot water, and will therefore maintain its elasticity to a greater extent than where it is exposed to the hot passing fluid.

The spindle 14 is surrounded by a bushing 32 which snugly fits an annular recess 31 65 in the casing part 2, said bushing acting as

a further support and guide to the spindle. The bushing 32 is shouldered as shown, and surrounding it is a spring 33 which forces the bushing outward against the hub of the operating lever 18, which latter is fitted over 70 the square end of the spindle and held in place by a washer 35 and cotter pin 36. The action of this spring 33, acting through the bushing and the operating lever 18, tends to hold the collar 15 tightly upon the packing 75 21 to assist in making and maintaining a steam and water tight joint, and at the same time preventing any rattling due to wear. This spring 33 is outside of the valve chamber and hence is not acted upon by the 80 hot steam and water therein; and moreover, may be replaced without opening the valve case. The rotation of the bushing 32 may be prevented by the employment of a screw 34, the end of which may enter a slot in the 85 edge of the bushing, but the pressure should not be sufficient to prevent the longitudinal adjustment of the bushing under the action of the spring.

From the foregoing construction, it will 90 be evident that a compact and practical construction for a quick-acting valve is provided, and that the heavy operating or swinging arm 22 is supported independently 95 of the valve seats, the latter being governed wholly by the valve pieces 26 and 27 which may be formed of bronze or brass, and these being light and freely adjustable, will insure at all times a tighter closure with less wear upon the seats than where the arm 22 100 is employed as forming a bearing with the inlet seat, as has heretofore been the customary practice. Furthermore, this construction of valve is reversible, as there is provided a clearly defined valve piece for 105 both ports, and in which both operate under exactly the same conditions. It will also be understood that as the heavy arm 22 is 110 guided at both ends, it maintains an accurate alignment with the operating stem, and removes all objectionable bending strain upon the said spindle, and consequently removes much of the wear of the spindle in its bearing, which has heretofore been caused 115 where such arms have been supported wholly by the spindle.

It will be observed that with my improvements the spindle is provided with an annular packed joint on the inside of the case 120 and in the valve chamber thereof, and this joint is maintained in tight condition by a coil spring on the outside of the valve casing surrounding the spindle, said spring pressing at one end upon the casing and at the other to applying pressure upon the hub 125 of the operating lever for creating a force which constantly tends to move the spindle outward and maintain the aforesaid tight joint; and it will be further seen that the 130 spindle so formed operates a swinging arm

which is recessed to receive the cylindrical body part of the valve piece for the outlet port which is spring pressed upon its seat, said valve piece arranged upon the same 5 side of the arm as is the spindle. The construction of the valve of the outlet port is such that the spring is shielded and received in a hollow recess in the back of the valve piece, the surrounding annular wall thereof 10 received in a circular aperture of the swinging arm, the construction insuring a yielding contact of the valve piece upon its seat to compensate for wear and permit independent seating, said operation not being interfered with by the spring action upon the spindle employed for rocking the arm and 15 valve piece.

While I have shown the construction of the valve in the form which I deem most preferable in practice, I do not restrict myself to the details thereof, as these may be modified without departing from the spirit of the invention.

Having now described my invention, what 25 I claim as new and desire to secure by Letters Patent, is:—

1. In a valve, the combination of the casting formed of a plurality of parts bolted together and providing an internal chamber 30 having inlet and outlet ports opening respectively through the opposite faces and terminating in opposed valve seats, a spindle journaled in one of the parts of the casing to one side of the port therethrough, a 35 swinging arm carried on the inner end of the spindle so as to be moved thereby and having an aperture through its free end in alinement with the ports, two valve pieces of the same cross section respectively working 40 in contact with the valve seats and having recessed hubs of the same diameter fitting the aperture in the swinging arm said hubs of a depth approximately equal to one-half the thickness of the swinging arm 45 so as to be wholly independent of each other and a spring disposed between the valve pieces and inclosed thereby for pressing the valve pieces upon their respective seats.

2. In a valve, the combination of the casting formed of a plurality of parts bolted together and providing an internal chamber having inlet and outlet ports opening respectively through the opposite faces and terminating in opposed valve seats and also 5 having a guide in its side wall extending in a plane parallel to the plane of the valve seats, a spindle journaled in one of the parts of the casing to one side of the port therethrough, a swinging arm carried on the inner end of the spindle so as to be moved thereby and having an aperture through its free end in alinement with the ports the said swinging arm also having its free end provided with a projection guided by the guide on the side 10 of the internal chamber for supporting said

arm against movement toward either valve seat, two valve pieces respectively working in contact with the valve seats and having hubs fitting the aperture in the swinging arm, and a spring disposed between the valve 70 pieces and inclosed thereby for pressing the valve pieces upon their respective seats.

3. In a valve, the combination of the casting formed of a plurality of parts bolted together and providing an internal chamber 75 having inlet and outlet ports opening respectively through the opposite faces and terminating in opposed valve seats, a spindle journaled in one of the parts of the casing to one side of the port therethrough having 80 an annular collar adapted to seat upon the inner part of the casing to form a tight joint, a bushing surrounding the spindle and guided in an aperture in the open face of the casing, an arm secured to the end of the 85 spindle for operating it and against which the bushing exerts a pressure, a spring surrounding the bushing for forcing it outward against the operating arm for causing the collar of the spindle to make a tight joint 90 in the casing, a swinging arm carried on the inner end of the spindle so as to be moved thereby and having an aperture through its free end in alinement with the ports, two valve pieces respectively working in contact with the valve seats and having hubs fitting the aperture in the swinging arm, and a spring between the valve pieces and inclosed thereby for pressing the valve 95 pieces upon their respective seats.

4. In a valve, the combination of a body casing having an internal chamber formed with inlet and outlet ports, means to control the outlet port spring pressed thereon, a spindle extending through the casing and 100 provided with a lateral arm for actuating said means said spindle restricted to rotate in a limited arc less than half a circle having an annular collar for making a tight joint on the inside of a casing, an arm secured to the outer end of the spindle for 105 rotating it, a bushing surrounding the spindle and guided in an aperture in the outer surface of the casing, and a spring arranged in the said aperture and extending 110 around the spindle for forcing the bushing outwardly to impart an outward spring action to the spindle for holding its collar tightly upon its seat.

5. In a valve, the combination of a body casing having an internal chamber formed with inlet and outlet ports, means to control the outlet port comprising an oscillatory arm and a spring pressed valve piece movable thereby, a spindle extending through 115 the casing for actuating said means said spindle having an annular collar for making a tight joint on the inside of the casing, an arm secured to the outer end of the spindle for 120 rotating it, and a spring extending 125

130

around the spindle with one end pressing against the casing for forcing the spindle outwardly to impart an outward spring action thereto for holding its collar tightly upon its seat.

6. In a valve, the combination of a body composed of a plurality of parts secured together to form an internal chamber provided with an inlet and an outlet opening in alinement through the said chamber, the inlet having an expansion chamber formed as a part of the body and of greater diameter than the inlet opening for the fluid and shaped to provide inclined walls converging in the direction of the axis of the inlet port where it opens into the internal chamber, whereby the flow of the fluid is given a conical direction so that it shall pass through the outlet port without injury to its walls, and means within the internal chamber for controlling the fluid passing through the ports.

7. In a valve, the combination of a casing formed of a plurality of parts bolted together and providing an internal chamber having inlet and outlet ports respectively through opposite faces and terminating in opposed valve seats and also having a guide in the side wall and extending in a plane parallel to the plane of the valve seats, a spindle journaled in one of the parts of the casing to the side of the port therein farthest from the side guide, a swinging arm carried by the spindle so as to be moved thereby said swinging arm having its free end guided upon the guide so as to be supported against movement toward either valve seat, and valve means movable with the swinging arm for controlling the flow through the ports.

8. In a valve, the combination of a casing having a valve chamber and inlet and outlet ports thereto, a spindle journaled in the casing to one side of the outlet port and having an annular collar on its inner portion seated upon the inner wall of the valve chamber, an arm within the valve chamber movable with the spindle when rotated, said arm having a bearing portion at its free end for a valve piece, a spring pressed valve piece sleeved in the bearing of the arm so

as to be moved laterally with it while maintaining spring pressure upon the outlet port valve seat, an arm secured to the outer end of the spindle to rotate it, and a spring coiled about the spindle and arranged between the casing and arm for imparting an outward spring pressure to the spindle for insuring the collar maintaining a tight joint and compensating for wear.

9. In a valve, the combination of a casing having a valve chamber and inlet and outlet ports thereto and also having a spindle bearing and annular packing recess to one side of the outlet port, an annular packing in the packing recess, a spindle journaled in the bearing and having an annular collar resting upon the annular packing, a spring actuated valve piece for controlling the outlet port, an arm movable within the valve chamber by the spindle for operating the spring actuated valve piece, a lever outside of the valve chamber and its casing for rotating the spindle, and a coil spring surrounding the spindle and arranged between the casing and the lever for insuring the collar of the spindle maintaining a tight joint with the packing, the construction providing independent spring action of the spindle and valve piece in the same direction.

10. In a valve, the combination of a casing having a valve chamber and inlet and outlet ports, a spring pressed valve piece to control the flow through the valve chamber, a spindle and arm therefor journaled in the casing and extending within the valve chamber for moving the valve piece transversely into alinement with the ports, said spindle having an annular collar for making a tight joint upon the inside of the chamber around the spindle bearing, means on the outer end of the spindle for rotating it, and a coil spring surrounding the spindle and arranged at the outside of the casing for forcing the spindle outward and maintaining its annular collar in tight coöperation with its seat, the spring actions of the spindle and valve piece being simultaneously operative without interference.

In testimony of which invention I hereunto set my hand, this 31st day of May, 1917.

R. M. HUNTER.
